COMBINED ELECTRIC SHAVER AND HEAD
PROTECTING CAP THEREFOR

E. Burton Benjamin, Highland Park, Ill., assignor to Electro Engineering Products Co., Inc.

Filed Sept. 22, 1969, Ser. No. 19,230

Term of patent 14 years

Int. Cl. D28—03

U.S. Cl. D95—3

FIG. 1

FIG. 2

FIG. 4

FIG. 3

FIG. 5

FIG. 1 is a perspective view of a combined electric shaver and head protecting cap therefor showing my new design;

FIG. 2 is a reduced scale right side elevational view;

FIG. 3 is a rear elevational view;

FIG. 4 is a top plan view; and

FIG. 5 is a bottom plan view.

I claim:

The ornamental design for a combined electric shaver and head protecting cap therefor, substantially as shown.
